UNITED STATES PATENT OFFICE.

CONRAD PANTKE, OF BROOKLYN, NEW YORK, ASSIGNOR, BY MESNE ASSIGNMENTS, TO LAMELLA ROOF SYNDICATE, INC., OF NEW YORK, N. Y., A CORPORATION OF NEW YORK.

ROOF CONSTRUCTION.

Application filed May 27, 1926. Serial No. 112,113.

This invention relates to roof construction and particularly to the method and means for the fabrication and putting into place of arched roofs having the structural characteristics of the roof and walls disclosed in the patent to Zallinger #1,483,037 granted February 5, 1924, in which the framework of the roof consists of a plurality of battens or lamella, similar in size and shape and similarly bored with bolt-holes or provided with other suitable fastening means so that they can be made in a factory and put together "on the job" without loss of time or preliminary fitting operations.

One of the objects of the present invention is the construction of such a roof, particularly for buildings of considerable height or length in which the use of scaffolding or other temporary supporting means or appliances is obviated.

Another object of the invention resides in the construction of a sectional roof in which the first section serves as a centering or supporting unit upon which the other sections are fabricated and then moved into position.

A further object of the invention resides in the method of accomplishing the above result.

Other objects of the invention will appear as the following description of the preferred embodiment thereof proceeds.

In the drawings:

Figure 1 is a cross section through the first-built or centering section of the roof, the ends of the walls being shown, upon which it is supported, and showing also another section being erected on top of the first section.

Figure 2 is a plan view showing the centering section, and in superposed relation the incomplete framework of one of the other sections.

Figure 3 is a plan view of one of the roof sections showing the longitudinal and transverse tie rods in position.

Figure 4 is a perspective view showing a fragment of one side of the centering section.

Figure 5 is a similar view showing one of the superposed sections shifted partly off of the centering section.

Figure 6 is a similar view showing the superposed section transferred from the carriage to the jack, one layer of bricks in the

retaining wall being removed to a sufficient depth to receive the jack.

Figure 7 is a similar view showing the superposed section in its final position.

Figure 8 is a cross section taken along the line 8-8 of Figure 4.

Figure 9 is a fragmentary cross section taken along the line 9-9 of Figure 5, and

Figure 10 is a fragmentary cross section taken along the line 10-10 of Figure 5.

Referring now in detail to the several figures, the numerals 1 and 2 represent opposite retaining walls on which are supported the sills 3 and 4 of the first-built or centering section of the roof, the same being represented in general by the reference character 5. Said section is constructed with a reticulated framework comprising lamella 6 disposed angularly towards one another, the ends of two lamellæ which are substantially in a straight line and meeting adjacent the middle of a lamella running angularly thereto. This arrangement of lamellæ is fully disclosed in the patent to Zallinger hereinbefore mentioned, and in itself does not form a part of the present invention, since the principles of the invention can be practiced with roofs having a variety of forms of framework construction.

The first or centering section is constructed in the usual manner, presumably upon suitable scaffolding, not shown, and after the frame work has been fabricated, it is covered with sheathing strips 7 to the extent indicated in Figure 2, the ends 8 of certain lamellæ being left free to join with the lamellæ of the adjoining section after the latter has been made and moved into its final position.

One strip of sheathing on each side of the centering section is omitted as shown at 9 in Figure 5, the purpose of said omission being to afford room for inserting the hooked ends of the hangers 10, shown in Figure 9 so that the latter may rest upon the upper edge of the next lower sheathing strip. The height and width of the arch of the first or centering section are preserved in the usual manner by means of tie rods 11 coacting with wedge blocks 24 upon which the sills 3 and 4 rest.

The second, and subsequent sections are similar to the first section, but put together upon it and afterwards shifted into final po-

sition, this requiring especial expedients and treatment which will now be described. The second section being of same degree of curvature as the first will not be concentric therewith when in superposed relation thereto but will be spaced at a greater distance from the centering section at its crown than at its sides. Therefore before building the second section suitable spacing battens 13, 14 and 15 are provided of progressively increasing depth as they approach the crown of the centering section. A suitable number of the hangers 10 are placed in position at the sides of the centering section, said hangers being furnished with rollers 16. The sills 17 of the second section are spaced in proper longitudinal position on the hangers 10, a removable track strip 18 being temporarily secured to said sills and bearing against the rollers 16. Said rollers are designed to take the thrust of the arch. The reticulated lamella framework is then built up, being secured to the sills and resting upon the battens 13, 14 and 15 giving to the second section the same shape as the first or centering section. The framework thus formed is denoted by the reference character 19 in Figure 2.

It is apparent that the second section, after the blocks 13, 14 and 15 have been removed relies entirely for the retention of its shape upon the counterthrust of the rollers 16. It is to be understood, however, that this counterthrust holds the arch against lateral expansion only, it being obvious that when the second section is entirely unsupported by the centering section the weight of the arch will cause a longitudinal elongation of the same due to the "lazy jack" action of the lamella so that provision must be made for temporarily holding the arch of the second section from longitudinal spreading with consequent flattening. This is done by the provision of removable tie-rods 21, Figure 2, which have hooked ends adapted to engage in the angles of the lamella. It is contemplated now to roll the superposed section longitudinally off of the underlying section. This is done gradually by any suitable means of power application, not shown. When the end of the second section begins to overhang the end of the centering section a tie-rod 11', Figure 5, is put in, and as the overhang increases other tie-rods are put in place preserving the shape of the arch. As the second section is rolled longitudinally off from the centering section it is supported upon carriages 22, one of which is represented in detail in Figure 10, consisting essentially of a yoke member carrying a roller 23. The carriage is here shown as conveniently resting under one of the wedge blocks 24. The roller 23 preferably engages a track strip 26 laid longitudinally upon the wall of the building. It may be found necessary, to ensure

the vertical position of the carriage, to provide bracing means such as the strut 27 shown in Figure 10 secured to one side of the carriage, and temporarily to one of the lamellæ. When the second section has been entirely removed from the centering or underlying section and is in the final position in which it is to reside, jacks, one of which is illustrated at 28 in Figure 6, are placed beneath it and elevated so as to take the weight of the arch from the carriages. In the present instance the front layer of bricks in the wall has been removed to receive the jack so that when the screw of the jack is lowered and sill of the arch will rest upon the retaining wall. When the weight of the arch has been transferred to the jacks on one side of the arch the carriages on that side are removed and the jacks lowered until the arch rests upon the wall. The same operation is then repeated for the other side of the section. If there is any misalignment in the position of the second section relative to the walls or to the centering section, the turnbuckles in the tie-rods 11 and 11' may be adjusted so as to draw in the ends of the arch or permit them to expand. When the centering section and the adjacent section are in proper alignment the unsheathed lamella 8 of one section are bolted or otherwise secured to the complementary lamella of the other section and the two sections of the roof thus united. Any number of roof sections may be made in this way, consisting of standardized parts and eliminating the need of scaffolding or other supporting means except in the building of the first or centering section, great economy in the cost of building a roof being thus obtained.

Although I have in the present embodiment of the invention shown a roof made with wooden lamella, it is to be understood that the invention may be practiced with equal success with roofs having commercial iron frameworks.

While I have in the above description disclosed what I believe to be a preferred and practical embodiment of my invention, it is to be understood that the specific details described are not limitative in their effect upon the invention but merely illustrative except in so far as they are expressly prescribed by the terms of the appended claims.

Having described my invention what I claim as new and desire to secure by Letters Patent, is:—

1. The method of constructing the subsequent sections of a sectional arched roof one of the sections of which is already constructed which consists in building a subsequent section upon the already built sections, supporting it thereupon, shifting the subsequent section relative to the already built section until it overhangs the latter, placing a tie-rod across the ends of the over-

hanging portion to hold the shape of the arch, and continuing the shifting operation and placing the tie-rods until the second section has reached a final position along side 5 of the already built section.

2. The method of constructing the subsequent sections of a sectional arched roof one of the sections of which is already constructed which consists in building a subsequent section upon the already built section, supporting it thereupon, shifting the subsequent section relative to the already built section until it overhangs the latter, placing a tie-rod across the ends of the 10 overhanging portion to hold the shape of the arch, continuing the shifting operation and placing the tie-rods until the subsequent section has reached a final position along side of the already built section, and simultaneously 15 with the shifting, and transferring the subsequent section to carriages.

3. The method of constructing the subsequent sections of a sectional arched roof one of the sections of which is already constructed which consists in building a subsequent section upon the already built section, supporting it thereupon, shifting the subsequent section relative to the already built section until it overhangs the latter, placing a tie-rod across the ends of the overhanging portion to hold the shape of the arch, continuing the shifting operation and placing the tie-rods until the subsequent section has reached a final position along side 20 of the already built section, and simultaneously with the shifting, transferring the subsequent section to carriages, substituting jacks for the carriages, and lowering the subsequent section to its permanent means 25 of support.

4. The method of constructing the subsequent sections of a sectional arched roof, one of the sections of which is already constructed which consists in arranging battens longitudinally of the already built section 30 of such height as to conform to the degree of curvature of the subsequent section when built and that of the already built section, building a subsequent section upon the al-

ready built section, supporting it upon said battens, and shifting the subsequent section to a final position along side of the already built section.

5. The method of constructing the subsequent section of a sectional arched roof one of the sections of which is already constructed which consists in arranging battens longitudinally of said already built section, said battens being of such height as to conform the degree of curvature of the subsequent section when built to that of the already built section, arranging counter-thrust members upon said already built section to receive the ends of the arch of the subsequent section, building a subsequent section upon the already built section, supporting it upon said battens and said counter-thrust members, and shifting the subsequent section to a final position along side of the already built section. 55 60 65 70

6. The method of constructing the subsequent sections of a sectional roof of reticulated lamella construction one of the sections of which is constructed with longitudinal hanger receiving slots adjacent the sills and which consists in placing hangers in said slots with casters exteriorly of the first section, placing the sills of the subsequent section upon the casters, building the subsequent section on its sills to be supported through the hangers and by the already built section, placing longitudinal tie-rods to prevent longitudinal spread of said section, shifting by longitudinally sliding on the casters of the hangers the subsequent section relative to the already built section until it overhangs the latter, placing tie-rods across the ends of the overhanging portion of said subsequent section as it is progressively shifted to hold the shape of the arch, and continuing the shifting operation until the subsequent section has reached its final position along side of the already built section. 75 80 85 90

In testimony whereof I have hereunto set my hand. 95

CONRAD PANTKE.
